Inventor

UNITED STATES PATENT OFFICE.

MARY J. ELLIOTT, OF PORT HURON, MICHIGAN.

DESIGN FOR A WORK-BAG.

SPECIFICATION forming part of Design No. 32,477, dated April 10, 1900.

Application filed March 15, 1900. Serial No. 8,850. Term of patent 7 years.

To all whom it may concern:

Be it known that I, MARY J. ELLIOTT, a citizen of the United States, residing at Port Huron, in the county of St. Clair and State of Michigan, have invented and produced a certain new and original Design for Work-Bags; and I do declare the following to be a full, clear, and exact description of the invention, such as will enable others skilled in the art to which it appertains to make and use the same.

The invention relates to a novel design for work-bags and is illustrated in the accompanying drawings, in which—

15 Figure 1 is a side elevation, and Fig. 2 is a top plan view.

As shown in the drawings, the leading or essential feature of my design consists of a tripod having hooks supporting a truncated 20 conical bag composed of interlocked rings and a perforated bottom.

1 denotes the tripod, consisting of three straight rods, the upper ends of which cross

each other and are provided with knobs 2. 25 3 denotes hooks projecting inwardly from said rods, and 4 denotes a hook projecting downwardly from the point of union of said rods.

5 denotes a bag composed of rings interlocked one with the other and made in the 30 form of a truncated cone. The uppermost interlocked rings have a chain 6, which is adapted to engage the hook 4 at the union of the rods, and 7 denotes rings engaging with the bag and supported by the hooks 3. 35

What I claim is—

The design for a work-bag, as herein shown and described.

In testimony whereof I have hereunto set my hand in presence of two subscribing witnesses. 40

MARY J. ELLIOTT.

Witnesses:

FRED J. WARGOWSKY,
CLARA C. RYAN.
